UNITED STATES PATENT OFFICE.

JAMES A. JAMISON, OF RUSSELLVILLE, ARKANSAS.

DESIGN FOR A BUGGY-TOP SPRING.

SPECIFICATION forming part of Design No. 33,380, dated October 16, 1900.

Application filed September 6, 1900. Serial No. 29,236. Term of patent 7 years.

To all whom it may concern:

Be it known that I, JAMES A. JAMISON, a citizen of the United States, residing at Russellville, in the county of Pope and State of Arkansas, have invented and produced a new and original Design for a Buggy-Top Spring, of which the following is a specification.

This invention relates to a design for a buggy-top spring; and the leading feature thereof consists in the design forming the subject-matter of the accompanying illustrations, wherein—

Figure 1 is a perspective view of the spring embodying the features of the design. Fig. 15 2 is a side elevation of the same.

The design is characterized by a pair of inclined arms 1 and 2, the arm 2 continuing into a depending curved extension 3, which ter-

minally connects with the end of the arm 1. At their inner extremities the arms continue 20 into depending loops 4 and from the latter another pair of arms 5, at an angle of inclination, reverse to the arms 1 and 2, the outer extremities of the said arms 5 also continuing into a curved depending extension 6. 25

Having thus described the invention, what is claimed as new is—

The design for a buggy-top spring, herein shown and described.

In testimony that I claim the foregoing as 30 my own I have hereto affixed my signature in the presence of two witnesses.

JAMES A. JAMISON.
